UNITED STATES PATENT OFFICE.

AUBREY M. KENNEDY, OF NEW YORK, N. Y.

SOUND TRANSMITTING AND RECEIVING APPARATUS.

Application filed March 6, 1926. Serial No. 92,684.

The object of the present invention is to provide a sound transmitting and receiving device suitable for use in conjunction with the transmitters or receivers of telephones, ear phones, or loud speakers of radio apparatus, etc., which shall result in increased volume as compared with the usual iron diaphragm, and which will also result in more natural transmission, or reproduction of sound waves.

The invention will be understood by reference to the accompanying drawings, in which—

Figure 1 is a sectional elevation of a radio loud speaker embodying improvements and Figure 2 is a horizontal section on the line 2—2, Figure 1.

Referring to the drawings, A represents a casing having an internal chamber for the reception of the magnet 1, having the pole pieces 2 which lie slightly below the top of the casing. The casing is threaded to receive a cap 3 which closes the casing except for a central outlet 3^x surrounding which is a neck 4 to receive a horn 5 or other transmitting device for the sound waves. The pole pieces 2 of the magnet lie immediately below and act upon the diaphragm directly, and the diaphragm may be the usual disk 30 of iron, or other material, as customary.

Stretched tightly over the upper surface of the diaphragm 6 and in contact therewith is a piece of elastic material, preferably thin leather, such as pig skin. In the present embodiment of the invention, the margin of the side pieces of elastic material are brought over the edges of the metallic disk and turned inward so that they may rest upon the shoulder formed by the top wall of the casing A. The cap 3 is provided with an annular shoulder 7, which overlies the top of the casing. Hence when the cap is screwed downward, with the diaphragm and its elastic covering in place, the covering is firmly secured in position.

As stated above, the pig skin, or other elastic covering for the metallic disk should be stretched upon the disk. This can be done in any suitable manner as by wetting the leather, or other material, prior to stretching

it upon the metallic disk and then securing the margins of the leather covering, as illustrated in Figure 1, prior to the drying of the covering. The drying operation will cause the covering to contract and the margins being held, the contraction will cause a stretching and tensioning of the material, as will be understood by further explanation. If desired, the inturned margins of the covering may be secured by glue, or otherwise, to the disk. In the use of the ordinary metallic diaphragm, there is a constant condition under which only part of the tones to be reproduced are acted upon naturally and without more or less distortion through the mechanical action of the disk and the nature of the material with which it is constructed. Such tones are given an unnatural stridency.

By means of the present invention a simple and effective device is provided for enabling reproduction of the sound waves, as in the transmission or amplification thereof, by two contacting members which have relatively different vibratory reactions and in which all of the sound waves passing from the metallic diaphragm are received and modified by the non-metallic member.

It will be understood that I have illustrated only one of the many possible forms of the invention, the drawings being merely illustrative of the principle of my invention, what I claim and desire to secure by Letters Patent, being as follows:

1. In sound transmitting and receiving apparatus, a casing having a sound discharge aperture, a metallic diaphragm within the casing and a thin leather material under tension and held in said casing adjacent the metallic diaphragm and co-extensive with its exposed area so as to completely shield the discharge outlet from the direct vibrations of the diaphragm.

2. In sound transmitting and receiving apparatus, a metallic diaphragm, and a thin tensioned elastic member directly applied to one face of the diaphragm and completely covering the effective area of said diaphragm including its axial portion.

3. In sound transmitting and receiving apparatus, a casing having a sound discharge

aperture, a primary diaphragm within the casing and adapted for magnetic vibration, and a secondary tightly stretched diaphragm intermediate the primary diaphragm and the sound discharge aperture and co-extensive with its exposed area, so as to completely shield the discharge outlet from the direct vibrations of the primary diaphragm, said secondary diaphragm being adapted to generate sound waves by its vibration and transmit them through said outlet. 10

In testimony whereof, I have signed my name to this specification.

AUBREY M. KENNEDY.
